Fig - 5

Fig - 6

Fig. 7

FIG. 1 is a front perspective view of a rafter supportable attachment for a circular saw, showing my new design;

FIG. 2 is an elevational view of the left-hand side of FIG. 1;

FIG. 3 is an elevational view of the right-hand side of FIG. 1;

FIG. 4 is a rear elevational view;

FIG. 5 is a top plan view; and,

FIG. 6 is a bottom plan view; and

FIG. 7 is a front elevational view of FIG. 1, and showing in broken line, for illustrative purposes only, a cir-

cular saw connected to the attachment, and a rafter straddled by the attachment.

I claim:

The ornamental design for a rafter supportable attachment for a circular saw, as shown and described.
